The ornamental design for a display panel or screen with a graphical user interface, as shown and described.

DESCRIPTION

FIG. 1 is a front elevational view of a first image of a first embodiment of a display panel or screen with a graphical user interface showing my new design;

FIG. 2 is a front elevational view of a second image thereof;

FIG. 3 is a front elevational view of a third image thereof;

FIG. 4 is a front elevational view of a fourth image thereof; and

FIG. 5 is a front elevational view of a fifth image thereof.

FIG. 6 is a front elevational view of a first image of a second embodiment of a display panel or screen with a graphical user interface showing my new design;

FIG. 7 is a front elevational view of a second image thereof;

FIG. 8 is a front elevational view of a third image thereof; FIG. 9 is a front elevational view of a fourth image thereof; and,

FIG. 10 is a front elevational view of a fifth image thereof.

The appearance of the transitional image transitions between the images shown in FIGS. 1 and 2, 2 and 3, 3 and 4, and 4 and 5. The appearance of the transitional image transitions between the images shown in FIGS. 6 and 7, 7 and 8, 8 and 9, and 9 and 10.

The process or period in which an image transitions to another forms no part of the claimed design. The outer dot-dash broken lines illustrate a display panel or screen and are a boundary of the claim. The inner broken lines showing various icons and portions of the graphical user interface illustrate portions of the article. None of the broken lines form part of the claimed design.
